UNITED STATES PATENT OFFICE

EARL M. ALLEN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY-TRAFFIC-CONTROLLING APPARATUS

Application filed August 20, 1930. Serial No. 476,544.

My invention relates to railway traffic controlling apparatus, and particularly to apparatus for controlling a manually operable railway switch from a remote point, such, for example, as the despatcher's office of a centralized traffic controlling system.

I will describe two forms of apparatus embodying my invention, and will then point out the novel features thereof in claims.

10 In the accompanying drawing, Fig. 1 is a diagrammatic view showing one form of apparatus embodying my invention. Fig. 2 is a view similar to Fig. 1, but showing a modification of portions of the apparatus illustrated therein and also embodying my invention.

Similar reference characters refer to similar parts in each of the views.

Referring first to Fig. 1, the reference character T designates a railway track which is provided with switches and signals controlled from a central point, such as the despatcher's office of a centralized traffic controlling system. Two switches S¹ and S² and a signal 25 C³ may, for example, be controlled by apparatus of this character, but the devices for controlling them are not shown in the drawing.

The reference character S designates a 30 manually operable switch which is normally locked in the normal position by a lock rod 7 coacting with a dog 6, which dog is operated by a manually operable lever G. This lever G is normally locked in the normal position by an electric lock L comprising a segment 3 35 fixed to the lever, a dog 4 coacting with the segment, and an electromagnet 5 arranged, when energized, to lift the dog 4 out of its locking position and to thereby release the lever G. The lever G is shown in its normal position wherein the switch is locked by the coaction of the dog 6 and the lock rod 7. When the lever G is reversed, the dog 6 is 40 withdrawn from its locking position, so that the switch is released. Certain contacts 12 and 15 are operated by the switch S, and other contacts 11, 16, 17, 18 and 21 are operated by the lever G. The manually operable 45 means for moving the switch S are not shown

in the drawing, for the reason that they form no part of the present invention.

Associated with the switch S is a normal control relay C^N and a reverse control relay C^R. These relays are similar to the signal control relays at a remote station in a centralized traffic controlling system, and they are controlled from the despatcher's office in such manner that either relay may be energized at will. Also associated with the switch S is a polarized indication relay P, and an approach locking relay A, the latter relay being controlled in any suitable manner so that it is normally energized but is deenergized when a train is approaching the switch S. Also associated with the switch S are a normal indication lamp I^N, a reverse indication lamp I^R, and an intermediate indication lamp I^M, the functions of which lamps will appear hereinafter.

As shown in the drawing, switch S is locked in its normal position, the normal control relay C^N is energized, and the reverse control relay C^R is deenergized. The polarized indication relay P is energized by virtue of a circuit which passes from terminal B of a suitable source of current, through the back point of contact 8 of relay C^R, front point of contact 9 of relay C^N, wire 10, normal lock contact 11, switch contact 12 in the normal position, wire 13, winding of relay P, wire 14, and switch contact 15 in the normal position, to terminal O of the same source of current.

The reverse circuit for relay P is closed when relay C^R is energized, relay C^N is deenergized, lever G is reversed, and switch S is reversed. This circuit is from terminal B, through the back point of contact 9 of relay C^N, front point of contact 8 of relay C^R, wires 16 and 17, reverse lock contact 18, switch contact 15 in the reverse position, wire 14, winding of relay P, wire 13, and the switch contact 12 in the reverse position to terminal O.

I will assume that with the parts in the 95 positions in which they are shown in the drawing, the despatcher desires to release switch S. To do this, he will deenergize relay C^N and energize relay C^R, thereby opening the normal circuit for relay P and closing the reverse circuit for this relay at the con- 100

tacts of the control relays. The reverse circuit for relay P will be open at contact 18 of lever G, so that relay P will become deenergized. Lock magnet 5 will then become energized, the circuit being from terminal B, through the back point of contact 9 of relay C^N, front point of contact 8 of relay C^R, wire 16, back contact 19 of relay P, front contact 20 of relay A, lever contact 21, and the magnet 5 to terminal O. Magnet 5 being energized, the locking dog 4 will be lifted out of engagement with the notch in the locking segment 3, so that lever G may be reversed to unlock the switch. After lever G is reversed 15 and before the switch is reversed, both terminals of relay P will be connected with terminal O of the source of current, the circuit being from terminal O, through switch contact 15 in the normal position, wire 14, winding of relay P, wire 13, switch contact 12 in the normal position, and lever contact 46 to terminal O. It follows that during this 20 transition period relay P is placed on short circuit and can not be falsely energized due to crosses or grounds.

After switch S has been reversed, the reverse circuit for relay P will become closed, so that the relay will again be energized in the reverse direction.

When the switch S is to be restored to its normal position, lever G will be returned to its normal position, and during the transition period wherein the lever G is normal and the switch S is reversed, relay P will again be placed on short circuit through a path which passes from terminal O, through switch contact 12 in the reverse position, wire 13, relay P, wire 14, contact 15 in the reverse position, and lever contact 47 to terminal O. The operator will then restore switch S to its normal position and the dispatcher will again energize relay C^N and deenergize relay C^R. The normal circuit for relay P will then again be closed.

Relay P may be used to control any suitable signaling or indicating apparatus. As here shown, this relay controls two signal relays D¹ and D², which signal relays in turn control two signals E¹ and E² governing traffic over the switch S. The circuit for relay D¹ includes a front contact 26 of a track relay F for the section in which the switch S is locked, but this circuit also includes a front contact 28 and a normal polar contact 29 of relay P. The circuit for signal relay D², likewise, includes a front contact 25 of track relay F, as well as a neutral contact 23 and a normal polar contact 22 of relay P. Both of these signal relays will usually be controlled in part from the dispatcher's office. The circuits for the control of the signals E by their relays D will be obvious from the drawing. The track relay F is energized in the usual manner by a track battery 2.

Relay P, together with the control relays

C, also controls the indication lamps I. When relay P is energized in the normal direction and control relay C^N is energized, the normal indication lamp I^N is lighted, the circuit being from terminal B, through the front point of contact 30 of relay P, polar contact 31 in the normal position, front contact 32 of relay C^N, and lamp I^N to terminal O. When relay P is energized in the reverse direction and relay C^R is energized, lamp I^R will be lighted, the circuit being from terminal B, through contact 30, polar contact 31 in the reverse position, front contact 33 of relay C^R, and lamp I^R to terminal O. During the transition period in which relay P is deenergized, lamp I^M will be lighted by virtue of a circuit which includes the back point of contact 30 of relay P.

Referring now to Fig. 2, the control relays C^N and C^R are governed in accordance with the usual circuits for controlling the switch relays of a centralized traffic controlling system. That is to say, these relays are controlled by a normal code relay K^N, a reverse code relay K^R, and a code operating relay J, as well as by the approach locking relay A. Relay J has a normally closed back contact 35-36, and a normally open front contact 35-37 which closes before the back contact opens when the relay becomes energized. The two code relays K are both normally deenergized.

The normal control relay C^N is provided with a pick-up circuit which passes from terminal B, through front contact 35-37 of relay J, front contact 38 of relay K^N, front point of contact 39 of relay A, and the winding of relay C^N to terminal O. This relay is provided with a stick circuit which passes from terminal B, through back contact 35-36 of relay J, back contact 42 of relay C^R, front contact 43 of relay C^N, and the winding of relay C^N to terminal O. Relay C^R is provided with a pick-up circuit which includes front contact 35-37 of relay J, contact 40 of relay K^R, front point of contact 41 of relay A, and the winding of relay C^R. Relay C^R is also provided with a stick circuit which includes back contact 35-36 of relay J, back contact 44 of relay C^N, front contact 45 of relay C^R, and the winding of relay C^R. An auxiliary stick circuit is provided for relay C^R, which circuit passes from terminal B, through front contact 35-37 of relay J, contact 38 of relay K^N, back point of contact 39 of relay A, front contact 45 of relay C^R, and the winding of relay C^R to terminal O. A similar auxiliary stick circuit is provided for relay C^N, which circuit includes contact 40 of relay K^R, and the back point of contact 41 of relay A.

The circuits for the control of relay P are the same in Fig. 2 as in Fig. 1. The circuit for the lock magnet 5, however, differs from the circuit shown in Fig. 1, be-

cause it is not necessary for this circuit to includes a contact of the approach relay A, for the reason that this relay controls the circuits for the control relays C. Consequently, the circuit for magnet 5 in Fig. 2 is from terminal B through back contact 9 of relay C^N, front point of contact 8 of relay C^R, wire 34, lever contact 21, and lock magnet 5 to terminal O. Wire 34, which is included in this circuit, is also included in the control circuits for relay P, and, consequently, it is only necessary to use four wires between the control relays and the switch with the apparatus shown in Fig. 2, whereas with the apparatus shown in Fig. 1 five wires are required between these two points.

As shown in the drawing, switch S is the normal position, and the other parts of the apparatus are in the positions corresponding to this condition of the switch. When the switch is to be released, the despatcher will energize relay K^R, and will then momentarily energize the code operating relay J. The energization of relay J will open the stick circuit for relay C^N and will also close the pick-up circuit for relay C^R. Relays K^R and J will then become deenergized, whereupon relay C^R will remain energized by virtue of its stick circuit. The lock L will then become released, so that the switch S may be reversed. When the switch is to be restored to its normal position, the despatcher will energize relays K^N and J, thereby deenergizing relay C^R and again energizing relay C^N. When the switch has been restored to its normal position, all parts of the apparatus will again assume the conditions in which they are shown in the drawing. In all other respects the operation of the apparatus shown in Fig. 2 is the same as that of the apparatus shown in Fig. 1.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. Apparatus for controlling a manually operable railway switch from a remote point, comprising a normal and a reverse control relay, a polarized indication relay, normal and reverse contacts operated by said switch, a manually operable lock for locking said switch in normal position, a magnet for releasing said lock, normal and reverse contacts operated by said lock, a normal circuit for said indication relay including a front contact of said normal control relay and a normal lock contact as well as a normal switch contact, a reverse circuit for said indication relay including a front contact of said reverse control relay and a reverse lock con-

tact as well as a reverse switch contact, a circuit for said magnet including a front contact of said reverse control relay and a normal lock contact, and indication devices for said switch controlled by said indication relay and by said control relays.

2. Apparatus for controlling a manually operable railway switch from a remote point, comprising a normal and a reverse control relay, a polarized indication relay, normal and reverse contacts operated by said switch, a manually operable lock for locking said switch in normal position, a magnet for releasing said lock, normal and reverse contacts operated by said lock, a normal circuit for said indication relay including a front contact of said reverse control relay and a reverse lock contact as well as a reverse switch contact, a normally energized approach locking relay associated with the switch, a circuit for said lock magnet including a front contact of said reverse control relay and a back contact of said indication relay as well as a front contact of said approach locking relay and a normal lock contact, and indication devices for said switch controlled by said indication relay and by said control relays.

3. Apparatus for controlling a manually operable switch from a remote point, comprising a normal and a reverse control relay, a normal and a reverse code relay both of which are normally deenergized but either of which may be energized at will, an approach locking relay associated with the switch, a code operating relay, a pick-up circuit for said normal control relay including a front contact of said approach locking relay and a front contact of said normal code relay as well as a front contact of said code operating relay, a pick-up circuit for said reverse control relay including a front contact of said approach locking relay and a front contact of said reverse code relay as well as a front contact of said code operating relay, a stick circuit for each control relay including a back contact of said code operating relay, and locking and indication means for said switch controlled by said control relays.

In testimony whereof I affix my signature.
EARL M. ALLEN.
